Primary Examiner — Cynthia R Underwood(74) *Attorney, Agent, or Firm* — ScienBiziP, P.C.(57) **CLAIM**

The ornamental design for a car seat hook, as shown and described.

DESCRIPTION

FIG. 1 is a front, right, and top perspective view of a car seat hook, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, right, and top perspective view of the car seat hook of FIG. 1 wherein a bracket of the car seat hook is vertical open.

The broken lines shown in the drawings are included for the purpose of illustrating portions of the car seat hook that form no part of the claimed design.
